UNITED STATES PATENT OFFICE.

MOSES A. KELLER, OF BROCKPORT, NEW YORK.

GRAIN-BINDER.

SPECIFICATION forming part of Letters Patent No. 230,705, dated August 3, 1880.

Application filed February 17, 1880.

To all whom it may concern:

Be it known that I, MOSES A. KELLER, of Brockport, in the county of Monroe and State of New York, have invented certain new and useful Improvements in Grain Harvesting and Binding Machines; and I do hereby declare the following to be a full, clear, and exact description of the same, reference being had to the accompanying drawings, which form part 5 of this specification, wherein—

Figure 1 is a front elevation of my invention. Fig. 2 is a top view, and Fig. 3 is an end elevation, of the same. Fig. 4 is a plan view, partly in section, of the automatic shipping 15 mechanism; and Figs. 5, 6, 7 are detail views of the same. Fig. 8 is a longitudinal sectional elevation of the binding-arm mechanism. Fig. 9 represents an equivalent construction of the differential shipping gear.

Similar letters of reference denote corresponding parts in the different figures.

The object of this invention is to improve the binding mechanism of harvesting-machines; and it more specifically consists in an 25 apparatus for varying the distances between the bundles by an automatic shipping mechanism and novel compound movement of the binding-arm.

The invention further consists in the construction and arrangement of various devices and combinations of devices, as hereinafter described and claimed.

As motion is imparted from the driving-wheel to the gearing operating the binding 35 mechanism, the speed of the latter must always bear a fixed relation to the space traversed by the driving-wheel; but as the grain growing in different places, even in the same field, often varies in quality, it is essential that 40 the speed of the binding mechanism should be adjusted to produce bundles of uniform size, or as near so as possible, and that, too, without the constant attention of the attendant or driver.

In previous machines of this class the variation of the distances between the bundles, so as to produce bundles of uniform size, has generally been accomplished by stopping the machine to substitute different gears, or by the 45 constant attention of the driver, who must start the binding mechanism at random, or else

let the machine discharge the bundles at equal distances apart for the entire round or field, regardless of the condition of the grain. When the attention of the driver is constantly divided it very frequently happens that the bundles are either too small or too large, causing derangements, breaks, delays, &c. 55

In my improvement all the foregoing difficulties are entirely overcome. It is only necessary for the attendant or driver to adjust, by means of a lever or handle placed within easy reach, the automatic shipping mechanism to the desired distance he wishes the bundles delivered. The distances between the 65 bundles to be delivered are indicated upon the locking mechanism of the adjusting-lever, and so arranged as to be in view of the attendant. After the lever has been adjusted, say, for a bundle at every eight feet, the machine will 70 continue to deliver the bundles at that distance apart in the forward movement of the machine. If the condition of the grain or any other reason makes it necessary that the bundles should be delivered less or more frequently, 75 it is only a matter of a moment for the driver to move the lever to the indicated number of feet he wishes the bundles delivered, and the automatic shipping mechanism will then cause the binding mechanism to deliver 80 the bundles regularly at that distance.

The adjustment of the shipping mechanism can readily be made while the machine is in operation, and one or two adjustments of the automatic shipping mechanism for each round 85 to be cut may suffice to produce practically uniform bundles throughout the whole field.

It will thus be seen that only a small amount of attention of the driver is required in controlling the binder. He can therefore give the 90 most of his attention to guiding his team, thereby doing more and better work than would be possible if he had to judge of the size of the bundles and start the binder for every bundle to be delivered. 95

That others may fully understand the construction and operation of my improvements, I will proceed to describe them in detail.

Referring to the accompanying drawings, A, B, C, D, E, and H represent so much of a harvesting-machine as is necessary to exhibit my 100 improvements in a practical working form;

but this particular construction of the harvester is not material. Any other construction or any ordinary harvester in use can readily be combined or fitted with the invention.

5 F and G denote the grain-receptacle, also of ordinary construction.

The main portion of my invention is plainly shown in Figs. 4, 6, and 8. In Fig. 4 the shaft and cog-wheel D'' may represent the main motor or axle of the drive-wheel A^c, which, by means of the wheel C'', gives a rotary motion to the shaft C''. This last shaft may be considered as the principal operating-shaft for the binding mechanism. It is provided with a 15 clutch-shipping mechanism, whereby the binding mechanism is put in and out of action.

The clutch S³ is feathered upon the shaft C'' and rotates with said shaft. The shipper S is held loosely in a groove around the clutch. 20 When resting with its projection S⁴ upon the end of the shaft g it is prevented from revolving with the clutch.

Mounted upon the end of the shaft C'' is a sleeve, t, which is provided at one end with 25 clutch-teeth to engage with the sliding clutch S³. Upon the other end of said sleeve is keyed a cog-wheel, a', which projects beyond the journal-box r. This wheel gears into a corresponding wheels, b'', which is mounted upon the lower 30 end of the shaft d'', which shaft communicates motion to the binding mechanism.

Mounted upon the sleeve t, between the journal-box r and the clutch, is an adjustable collar, P'', provided with a projecting stud or pin, 35 q, which engages with the incline S² of shipper S, to move and hold the clutch S³ out of engagement at each complete revolution of the sleeve. The sleeve being fitted loosely upon the shaft, it becomes stationary at the moment the 40 clutch is disengaged, and hence all the binding mechanism is out of action.

The object of making the collar P'' adjustable is to stop the binding arm and mechanism at any desired point after the binding has been 45 completed. The adjustment is made by simply loosening the set-screw w, moving the collar with the pin q to the proper point, and tightening up again the set-screw.

Rigidly secured to the shaft C''' are differential gear-wheels d e f, which gear into and 50 drive the differential wheels a b c, which wheels run loose upon the tubular shaft g, except under certain conditions, which I will presently explain.

55 The object of the differential gears is to give a differential motion to the shaft g, which shaft has for its function to operate the shipper S by means of the projecting stud or pin m. Said shaft is only rotated when the pin i of the sliding shaft h is brought in contact with one of the wheels a b c, which wheels are provided with several keyways, l. (See Fig. 5.)

The pin or key i projects through a slot in the shaft g.

60 When the shaft h is moved endwise the pin or key i will engage with one of the keyways l of the desired wheel, and thereby cause

the shaft g to rotate with the wheel thus secured; but when the pin or key i stands in one of the free chambers J'', as shown in Fig. 70 4, the shaft g will become stationary. The main object, however, of the free chambers J'' is to prevent all danger of breaking any part of the mechanism in shifting from wheel to wheel while the machine is in motion. 75

Fig. 9 represents an equivalent construction of the differential wheels. This plan will allow the wheels to be brought into a more compact form when, for any reason, it is necessary to have a considerable number of them or 80 there is not sufficient space to admit them in the plan shown in Fig. 4.

When the shaft g rotates it will at each revolution raise the shipper S, by means of the pin m coming in contact with the projecting flange 85 S⁴ of shipper S, and thereby throw the shipper from the pin q of collar P'', when the spring P³ will drive the clutch S³ into engagement with the sleeve t and start the binding mechanism, in the manner before described. 90

To fully understand the object of the differential gears, suppose the wheels e and f are proportioned to give one revolution to the shaft g to every eight-feet traverse of the driving-wheel or forward movement of the machine. 95 This will cause the binding mechanism to deliver the bundles at that distance apart. If the wheels b e will cause one revolution of the shaft g in every ten-feet advance of the machine the bundles will be delivered at that 100 distance apart. The other pair may be proportioned to trip the shipper every twelve feet, and so on for as many different wheels as may be employed. The gears can, of course, be proportioned to give any desired distance, and the 105 invention is not limited to the above distances.

For the convenience of the attendant in adjusting the automatic shipping mechanism to the distances he wishes the bundles to be delivered while the machine is in motion, I apply a lever or handle, T, to the shaft h, and arrange it conveniently within reach of the driver or attendant, and also provide a stopping or locking mechanism, V, for the lever T. The notches or holes of the stop V are 110 marked to indicate the distance between the bundles. If the lever is moved to allow the pin to enter the hole marked 8 the shipper will be automatically tripped at every eight-feet advance of the machine. The spring V' 115 prevents the lever from moving of its own accord, and allows an easy adjustment of the lever at all times, but, in connection with the pin, positively locks the lever when placed at the proper position. The lever is pivoted near 120 its middle to a suitable support, W; but it is obvious that the lever may be constructed and arranged in a great variety of ways and forms without departing from the spirit of my invention. 125

If, for any reason, it is desirable to stop the operation of the automatic shipping mechanism, it is only necessary to move the lever to the holes in the stop V which are marked with 130

the 0. Then the pin 1 on the sliding shaft *h* will stand in one of the free chambers *J*''', and the wheels *a b c* will be free to turn upon the shaft *g* without giving motion to it, thus preventing the automatic tripping of the shipper *S*.

Pivoted to the shipper *S* is a rod, *R*, which connects the vibrating crank *Q* with the shipper *S*. At the outer end of the same shaft to which the crank *Q* is secured is a crank, *P*, which, by means of a rod, *M*, bell-crank *N*, and rod *O*, connects with the foot-lever *L*. This provides a means by which the driver may start the binding mechanism independent of the automatic shipping mechanism.

15 I will now proceed to describe the mechanism for operating the binding-arm.

It will be observed, by reference to the dotted line *S*'', Fig. 1, that the extremity of the binding-arm *X* has a peculiar compound movement, similar to that of the human arm, in encircling a gavel of grain for the purpose of binding the same.

Similar binding-arms have been and are in use with wire binding or twisting mechanism; but their movement and their operating mechanism are entirely different.

The first object of the peculiar motion of the extreme point of my binding-arm is to successfully adapt it to binding with cord instead of with wire, although this motion could readily be used for wire as well as for cord. By my plan of giving the arm a peculiar vertical and horizontal movement, with periods of rest, I can readily adapt it to any kind of tying mechanism, as I can form the cam in the revolving cylinder *D*'' in such a manner as to give the arm any desirable vertical movement, and by my plan of producing the horizontal vibration of the arm I can also cause the arm to remain stationary at either end of its horizontal stroke, so that the arm may descend perpendicularly through the grain, then swing horizontally outward with the bundle, and remain stationary during the operation of uniting the ends of the applied band without arresting the motion of the operating mechanism. I can also give the arm any amount of vertical movement in either direction during the operation of uniting the ends of the applied band without affecting the horizontal movement of the arm or its periods of rest. These are important points in connection with cord-binding, which must be considered before success can be attained.

55 I do not propose to limit this invention to any particular tying mechanism, and therefore do not show any. In practice, I locate the tying mechanism at the rear end and under side of the grain-receptacle, in close proximity to the extremity of the binding-arm at the conclusion of its outward stroke, with a bundle preparatory to binding, and operate said tying mechanism by any suitable connection from the wheel *e*'' or shaft *d*'', as the case may require.

The binding-arm *X* is pivoted to the vertical vibrating shaft *f*''. (See Fig. 8.) This shaft

is free to vibrate in the support *Z*, and is rigidly secured to the horizontal vibrating bar or arm *T*''. On the lower end of the shaft *f*'' is loosely mounted the cam-cylinder *D*''. To the upper surface of the cam-cylinder is rigidly secured the cog-wheel *e*''', which gears into the wheel *e*'', thereby communicating motion to the cam-cylinder, which turns freely upon the shaft *f*'', and is held in place by the nut *f*'''.

Pivoted to the arm *X* is the rod *Y*, which is provided at its lower end with a roller to travel in the camway 2. By this means the rotation of the cam-cylinder causes the rod *Y* to move the extremity of the arm *X* up and down.

Pivoted to the vibrating bar or arm *T*'' is a slotted pitman, *n*'', (see Fig. 2,) which is operated by a suitable wrist-pin on the cog-wheel *e*''. This pitman gives the horizontal vibrating motion to the binding-arm with its periods of rest during the operation of binding a bundle. The vibrating bar or arm *T*'' extends laterally beyond the point of the binding-arm when it is down, and acts against the same to assist in moving it outward with the bundle. (See *T*'', Fig. 2, and dotted line, Fig. 8.)

The rod *Y* passes through a guide attached to the arm *T*'', and is thus held in the proper relation to the cam-cylinder and binding-arm during the rotation of the former, so as to control the vertical vibration of the latter at all points.

Having described my invention, what I claim as new is—

1. In combination with the binding mechanism of a harvester, a series of differential gear-wheels mounted loosely upon a shaft, a device for engaging any one of said wheels with said shaft, and a pin, *m*, or its equivalent, secured to and rotating with said shaft to control the shipping mechanism, substantially as and for the purpose set forth.

2. The combination, with the binding mechanism of a harvesting-machine, of a series of differential gear-wheels mounted and grouped loosely upon a shaft, corresponding wheels in the train of gear which drives said binding mechanism, whereby motion is communicated to said differential gears, a mechanism for controlling said differential gears, and a shipping mechanism controlled automatically by said differential gears to determine the distances between the bundles, as set forth.

3. In combination with an automatic grain-binding mechanism, a series of differential gears, a clutch, and intermediate mechanism under control of said differential gears, whereby the binding mechanism is set in motion, as and for the purpose set forth.

4. In combination with the automatic binding mechanism of a harvester, a series of differential gear-wheels, a clutch in the train of gear which drives the binding mechanism, intermediate operating mechanism controlled by said differential gears, and a mechanism for automatically disengaging said clutch at the conclusion of each binding operation, substantially as set forth.

5. In combination with an automatic binding mechanism, a clutch in the train of gear which drives said binding mechanism, a shipper pivoted upon said clutch, a series of differential gear-wheels, and intermediate operating mechanism for operating the shipper to determine the distances between the bundles, as set forth.

6. In a grain-binding machine, the differential gear-wheels *a b'c*, with or without the chambered rims *K*, in combination with the mechanism for automatically tripping the clutch - shipping mechanism, substantially as described.

15 7. The combination of the tubular shaft *g*, provided with a pin, *m*, or its equivalent, for moving the shipper, a series of differential gear-wheels mounted loosely upon said shaft, a sliding adjustable shaft, *h*, within the tubular shaft, a lever, *T*, connected to said sliding shaft, and a stop, *V*, for locking the lever and shaft in position, substantially as and for the purpose set forth.

8. The combination of an automatic binding mechanism, an automatic revolving sliding clutch, a vibrating shipper turning upon the clutch, a revolving pin or cam, *m*, for operating the shipper, a series of differential gears for operating the pin or cam *m*, a sliding shaft 25 for controlling the gears, a lever for controlling the shaft, and a stop for holding the same, the whole constructed, combined, and arranged substantially as and for the purpose set forth.

9. The combination, in an automatic grain-binding mechanism, of a horizontal and vertical vibrating binding-arm pivoted upon a vertical stationary vibrating shaft, *f''*, a geared revolving cam-cylinder, *D³*, mounted loosely upon the shaft *f''*, for imparting a vertical vibrating motion to the extremity of the binding-arm, a horizontal gear-wheel, *e''*, for driving the cam-cylinder and vibrating the shaft *f''*,

and bar *T³*, these members being constructed and combined for operation substantially as described.

10. The combination of a horizontal and vertical vibrating binding-arm pivoted upon a vertical stationary vibrating shaft, *f''*, a revolving cam-cylinder, *D³*, and the connecting-rod *Y*, pivoted to the binding-arm *X*, and provided at its lower end with a roller for engaging the cam-groove *2*, all constructed and combined substantially as and for the purpose set forth.

11. The combination of the cam-cylinder *D³* 55 on the shaft *f''*, the rod *Y*, with its roller, to engage the cam-groove *2*, the cog-wheels *e''* and *e'''*, the pitman *N''*, and the bar or arm *T³*, all constructed and arranged for operation substantially as shown and described, for the 60 purpose of giving to the binding-arm *X* a vertical and horizontal vibration and a variable period of rest.

12. The combination of the stationary frame *Z*, supporting the vertical shaft *f''*, the cam-cylinder *D³*, mounted upon said shaft below the supporting-frame *Z*, a bar or arm, *T³*, rigidly secured upon the shaft *f''*, between the supporting-frame and the cam-cylinder, and the rod *Y*, guided by the bar or arm, these members being combined and arranged for operation substantially as shown and described, and for the purpose set forth.

13. The combination of the binding-arm mechanism, whereby a variable horizontal and vertical vibrating motion is imparted to it, and mechanism for suspending its movement during the operation of uniting the ends of the band without arresting the motion of the driving mechanism, substantially as described. 75
